FRICTION ROPE

Application filed September 26, 1929. Serial No. 395,328.

My invention relates to a specially constructed friction and tension rope.

The rope disclosed in my invention is especially adapted to be used in connection with the let-off motions of weaving looms and knitting machines.

In such machinery a taking-up and let-off motion act in conjunction to draw the warps forward at a suitable rate and tension. The 10 take-up motion of the machine is controlled by a positive ratchet gear which determines the rate with which the warp is drawn forward by the take-up roll, while the let-off motion is controlled by a counter weighted 15 friction rope wrapped around the brake pulley of the let-off roll, the friction of which determines the warp tension.

The uniformity of weave is entirely dependent on the amount of friction existing 20 between the rope and the pulley which latter is generally known as the beam ruffle.

The friction between any length of rope and the ruffle is greater near the tight side of the rope and gradually decreases around 25 the ruffle towards the slack side, and the tension at the slack side of the rope will equal the difference between the tension at the tight side and the friction.

The rope friction however varies with the 30 warp tension during the opening and the closing of the yarn shed which occurs for each cross-thread or pick inserted in the warp by the shuttle.

When the yarn shed is closed the warp is 35 slack and the tension of the rope at the tight end, which is the counter weight supported by the rope at this end, equals the tension at the slack end of the rope.

When the yarn shed is opened the warp 40 tension increases and the tension in the rope at the slack end also decreases until a point is reached at which the rope will slip around the pulley.

In plain weaving during the opening of 45 the yarn shed the let-off roll is turned through a considerable angle. Due to the elastic property of a fiber rope this only results in slip at the end of the motion, then as the shed closes and the warp tension decreases the let-

off roll turns back taking up the slack and keeps the warp tight.

The more the rope is wrapped around the beam ruffle, the greater will the angle be through which the beam is turned without 55 slippage, and it has been found necessary to wind the rope from three and a half to four and a half turns around the ruffle in order to prevent slippage.

Where so many turns around the ruffle are 60 employed the arc of contact between the rope and the ruffle becomes so great that an excessive friction will occur, and it is either necessary to employ lubricating means or to reduce the number of rope wraps around the 65 ruffle, in which latter case special warp tensioners must be employed.

Even dry lubricants like graphite and chalk are liable to soil the fabric and also 70 their abrasive action on the rope shortens the life thereof.

I have discovered that when the surface of a rope is made to comprise a plurality of helically wound rope elements or strands of 75 which one or more have the outside diameter of the helix larger than the remaining ones, such a rope may be wrapped around the ruffle the required number of turns without giving rise to an excessive friction.

In the drawing:—

Figure 1 is a cross section of a three strand 80 rope of my construction.

Figure 2 is a short length of the three strand rope showing the strand arrangement thereof.

Figure 3 is a cross section of a four strand 85 rope of my construction.

Figure 4 is a short length of the four strand rope showing the strand arrangement thereof.

Referring to the drawing in which like reference characters designate corresponding parts, 1 represents the three strand rope proper.

This rope is shown comprising three 95 strands. One of the strands 2 comprises twelve yarns while the strands 3 and 4 contain only ten yarns each. The yarns are preferably made up of fibers twisted together.

The strands are twisted together and the 100

outside diameter A of the strand 2 is larger than the outside diameter B of the strands 3 and 4.

Figures 3 and 4 show the construction of a four strand rope 5.

This rope comprises four strands, which are twisted together and the outside diameter of the strands 6 and 7 on the drawing denoted as C is greater than that of the helices described by the smaller strands 8 and 9 on the drawing denoted as D.

It is to be understood that when a rope after my construction is wrapped around the beam ruffle only the large surface strands are in contact with the ruffle and the arc of contact between the rope and the ruffle will be materially reduced.

The tension of the warp is regulated by the friction between the rope and the beam ruffle, and this friction depends on the counter weight supported by the rope, on the coefficient of friction between the rope and the ruffle, and on the arc of contact between the rope and the ruffle.

As the arc of contact is practically cut in half, in a rope of my construction it is possible to wrap around the ruffle a rope having a length approximately double that of the conventional rope without setting up an undue friction and the angle through which the let-off roll will turn as the rope stretches through the opening of the yarn shed without slippage will be approximately doubled.

It is also to be noted that in a rope of my construction the wear of the rope will be confined to only the larger rope strand elements, while the remaining ones will remain unworn and of unimpaired strength.

It is also to be understood that by making each of the strands out of a number of relatively hard twisted yarns the wearing quality of the strands becomes greater than if each of the strands were composed of one single large yarn.

With my construction only the surface yarns of each strand are in contact with the ruffle while the inner yarns thereof are protected and of unimpaired strength.

I do not wish to be understood as limiting myself to the specific details of construction as it is manifest that variations and modifications may be made in the adaption of the device to various conditions without departing from the spirit and scope of my invention.

55 I claim:—

A fiber rope comprising a plurality of helical surface strands, each of said strands composed of a plurality of yarns and the outside diameter of the helix of a number of said strands being larger than the diameter of the remaining ones.

ROBERT S. O. LAWSON.
